LAMP SOCKET AND LAMP SOCKET
INSTALLATIONScipione M. Del Camp, Maywood, Ill., assignor to
Cinch Manufacturing Corporation, Chicago,
Ill., a corporation of Illinois

Application January 8, 1937, Serial No. 119,598

4 Claims. (Cl. 173—339)

My invention relates to lamp socket installations and to lamp sockets for the same.

Referring to the illustration, in which I have shown a preferred embodiment of my invention:

5 Figure 1 represents a top plan view of my improved lamp socket installation showing a lamp socket, with lamp bulb attached, secured to a supporting panel;

Fig. 2 is a bottom plan view of the installation shown in Fig. 1;

Fig. 3 is an elevational view of the installation shown in Figs. 1 and 2;

Fig. 4 is a view similar to that of Fig. 3 but with the installation turned 45°;

15 Fig. 5 is a section taken along the line 5—5 of Fig. 1;

Fig. 6 is a section taken along the line 6—6 of Fig. 1; and

Fig. 7 is a fragmentary section taken along the 20 line 7—7 of Fig. 1.

An object of my invention is to provide a lamp socket of inexpensive construction which may be detachably secured to a panel in such a way that a circuit may be passed through a lamp bulb held 25 by the socket without need for attaching any wire to the lamp socket proper. My preferred form of installation, as illustrated and described, is useful in dial illumination and in such other cases where it is impossible to remove a lamp 30 bulb for replacing it, because with my improved construction the socket member assembly of the installation may be quickly and easily removed from the support, a lamp bulb replaced and the 35 socket member assembly once more secured to the support without any interference or disturbance with the wiring.

Referring to my preferred form of installation as illustrated in the drawing, I have provided a metal tubular socket member 1 having an open 40 front end to receive the base 2 of a lamp bulb 3 and a rear end provided with an aperture 4 through which extends a spring-actuated contact member 5 adapted to engage in electrical connection with a central contact element 6 on 45 the bottom surface of the lamp base 2. A metal attaching member 7 is secured to the socket member 1 and is in electrical connection with the socket member. The attaching member 7 has means for detachable engagement with a metal 50 ring 8 which is in permanent assembly with a metal support 9. A disk support 10 of non-conducting material is disposed between the ring 8 and the support 9 for carrying the ring and insulating the ring from the support. A lead-in terminal 11 is in electrical connection with the

ring 8. A metal grounding member 12, in electrical connection with the contact member 5, is assembled at the opposite end of the socket 1 from that holding the lamp bulb 3. The grounding member 12, in my preferred form, has portions engaging the metal support 9 for completing a circuit through the lamp bulb.

Referring in more detail to my socket member, I have shown one which is adapted particularly for use with a single contact lamp of the type now 10 almost universally used in automobile installations. It should be remembered, however, that my invention is not limited to this particular type of socket as changes and alterations may be made in the socket such, for example, as providing another way of completing the circuit from the contact member 6 of the lamp base to a lead-off means which would fall within the scope and spirit of my present invention.

My socket installation, as illustrated, comprises 20 a metal tube-like part 1 having, in my preferred form, bayonet slots 13 (Fig. 7) at one end adapted to receive lateral projections 14 of the lamp base for holding the lamp base in the socket member. A tubular rivet 15 extends through the aperture 4 25 of the other end of the member 1 having a head portion 16 disposed inside the member 1 and engaging the outside surface of an insulating washer 17 (Figs. 5 and 6). The washer 17 bears upon the material of the member 1 adjacent the aperture 4 and has an aperture 18 of less diameter than the aperture 4 of the member 1 whereby the barrel portion of the rivet member 15, which passes through the aperture 18 of the washer 17, is insulated from the member 1. The outermost 30 end of the rivet 15 is turned over to form a head portion 19 engaging the outside surface of a base portion 20 of the grounding member 12 in assembly with the socket member. As a result of my particular construction the grounding member 12 is in electrical connection with the rivet 15. An insulating washer 21 disposed between the base portion 20 of the grounding member and the socket 1 serves to insulate the grounding member from the socket. It will be noticed that the insulating washers 17 and 21 and the base portion 20 of the grounding member are maintained in fixed assembly with the socket member between the head portions 16 and 19 at opposed ends of the 45 rivet 15. Arm portions 22, integral with opposite sides of the base 20, extend from the base 20 in the direction of the lamp bulb for contact with the support 9. The free ends of the arms 22 may be bent inwardly toward each other, as most 50 55

clearly shown in Figs. 3 and 5, for a reason which will be hereinafter described.

As a means for completing the circuit connection between the rivet 15 and the central contact 6 of the lamp base 2, I have provided an elongated metal contact member 5 having a barrel 23 mounted within the bore of the rivet 15 and adapted to slide longitudinally relative to the rivet (Figs. 5 and 6). The barrel 23 of the contact member 5 fits relatively tightly within the bore of the rivet 15 thereby providing a permanent electrical connection between the parts. A head portion 24 is provided at one end of the member 5 and disposed within the socket member for engagement with the contact 6 of the lamp base. A flared portion 25 is provided at the opposite end of the contact member from the head portion 24. The portion 25 is disposed outside the outer end of the rivet 15 and is of larger diameter than the bore of the rivet so as to abut the outer end of the rivet and thereby limit longitudinal movement of the contact member through the rivet when the lamp is disconnected from the socket member. A coil spring 26 (Figs. 5 and 6) surrounds the barrel 23 of the contact member and is disposed between the head portion 16 of the rivet and the head portion 24 of the contact member, as most clearly shown in Figs. 5 and 6. During connection of the lamp base 2 with the socket 1 the contact member 5 is moved longitudinally so that the flared end of the contact member projects beyond the outer end of the rivet as shown in Figs. 3-7. At the same time the coil spring is contracted so as to maintain the head portion 24 of the contact member 5 in engagement with the contact 6 of the lamp base so long as the projections 14 of the lamp base are in proper registration with the bayonet slots 13. The attaching member 7 is in the form of a metal collar having a portion press-fitted to the socket member and a flange 27 (Figs. 3-7). A plurality of resilient shouldered fingers 28 are formed integral with the flange and extend from beneath the flange, in my preferred form, in the form of an annular series for spring engagement through the metal ring 8, as most clearly shown in Fig. 7.

A preferred form of my support installation as illustrated consists of a metal support 9 having a relatively large circular aperture 29 therein. A supporting disk 10 of insulating material is secured to the under side of the support 9 through an attaching means which may be rivets 30 (Fig. 6) extending through the support and the insulating disk. The insulating disk 10 has oppositely disposed apertures 31 disposed beneath the material of the support 9 adjacent the aperture 29, as most clearly shown in Fig. 5. An aperture 32 is formed in the insulating piece 10 between the apertures 31 and beneath the aperture 29 of the support. The metal ring 8 is secured to the material of the insulating disk 10 adjacent the aperture 32 and in final position provides a metal border around the aperture 32. The wiring terminal 11 is preferably formed integral with the ring 8 and extends from the ring 8 through the aperture 29 of the support to a position on the opposite side of the support from the disk 10. An aperture 33 may be formed in the terminal 11 for soldering a wire to the terminal.

In attaching my socket assembly to the support the socket assembly is moved toward the support so that the arms 22 of the grounding member 12 extend through the apertures 31 of the insulating disk 10. During this action the fingers 28 of the attaching member 7 extend through the circular

ring 8 defining a central aperture which is larger than the diameter of the socket member 1 but smaller in diameter than the circle in which lie the outside edges of the shouldered fingers 28. Pressure upon the socket assembly is continued until the flange 27, which is of larger diameter than the aperture defined by the ring 8, is pushed flush against the insulating disk 10. The socket assembly is now held firmly to the support assembly through the spring action of the fingers 28. At the time the arms 22 of the grounding member 12 are extended through the apertures 31, the inturned free end portions of the arms 22 engage the material of the support 9 adjacent the aperture 29 acting as a cam for contracting the arms during passage of the arms through the last-mentioned aperture. When the shouldered fingers 28 of the attaching member 7 are in final snap fastener engagement the arms 22 of the grounding member expand through natural resiliency of the grounding member to engage under spring tension the material of the support 9 adjacent the aperture 29. After my socket assembly is in attachment with the support assembly, electrical energy, introduced to the wiring terminal 11, passes to the base 2 of the lamp through the ring 8, the attaching member 7 and the metal socket member 1. Circuit through the lamp is completed through the contact member 5 in engagement with the contact 6 of the tube base, the rivet 15 and the grounding member 12.

Various changes and alterations might be made in the general form and arrangement of parts described without departing from the invention. For that reason I do not wish to be limited by the preferred form of my invention illustrated and described, but shall consider myself at liberty to make such changes and alterations as fall within the scope of the following claims.

I claim:

1. A lamp socket installation comprising a metal support, a metal ring assembled with said support and insulated therefrom, a positive wiring terminal in electrical connection with said ring, a metal tubular socket member having means at one end for receiving and holding a lamp base whereby said lamp base is in electrical contact with said socket member, and said socket member having attaching means in detachable engagement with said metal ring whereby said socket member is detachably secured to said metal support and in electrical connection with said wiring terminal, and said socket member having a negative lead in electrical connection with said lamp and a conducting member for detachably grounding said negative lead to said metal support contemporaneously with the engagement of said attaching means with said metal ring whereby said socket member may be completely detached from said metal support without disturbing the wiring of said installation.

2. A lamp socket installation comprising a metal support having an aperture therethrough, a piece of insulating material secured to the lower side of said support and having an aperture disposed beneath the aperture of said support, a metal ring carried by said insulating piece and disposed adjacent the aperture thereof, a positive wiring terminal in electrical connection with said ring and disposed on one side of said support, a metal tubular socket member disposed on the other side of said support from said wiring terminal, said socket member having means at one end for receiving and holding a lamp base whereby said lamp base is in electrical contact

with said socket member, and said socket member having attaching means in detachable engagement with said insulating piece through the metal ring thereof whereby said socket member is detachably secured to said insulating piece and in electrical connection with said wiring terminal, and said socket member having a negative lead in electrical connection with said lamp, and a conducting member for detachably grounding 5 said negative lead to said metal support contemporaneously with the engagement of said attaching means with said metal ring whereby said socket member may be detached from said insulating piece without disturbing the wiring of 10 said installation.

3. A lamp socket installation comprising, in combination, a socket-supporting means including at least two metal members each of which may be connected to opposite sides of an electric circuit and an insulation member interposed 15 between the two metal members, one of said metal members having a socket-receiving aperture, a lamp socket having a metal shell provided with snap fastener-like attaching means adapted to 20 pass into said aperture and detachably engage one of said metal members in electrical contact, a lamp bulb carried by said shell and in electrical contact with said shell, a contact for said bulb insulated from said shell and connected with 25 yieldable metal plate-contacting means adapted to make detachable electrical contact with the other metal member of said socket-supporting means, said lamp bulb and socket thereby being 30

attachable and detachable as and for the purpose described.

4. A lamp socket installation comprising a metal support having an aperture therethrough, a piece of insulating material secured to the lower side of said support, said insulating material having a central aperture disposed beneath the aperture of said support, and at least one aperture spaced from said central aperture, a metal ring carried by said insulating piece, said ring disposed adjacent the central aperture of said insulating piece so as to rim said last-mentioned aperture, a wire-receiving terminal integral with said metal ring, a metal tubular socket member having a means at one end for receiving a lamp base, an attaching member secured to said socket member and in electrical connection therewith, said attaching member having means in engagement with said metal ring whereby said socket member is secured to said support, a contact member having a portion within said socket member adapted for electrical contact with said lamp base for completing a circuit through said lamp, and a metal grounding member having a base portion secured at the other end of said 25 socket member from the end of said socket member receiving said lamp, said base portion being in electrical connection with said contact member, said metal grounding member having at least one arm portion extending through said insulating piece for engagement with said metal support whereby said circuit is grounded to said support. 30
